UNITED STATES PATENT OFFICE.

VERNON ROYLE, OF PATERSON, NEW JERSEY.

TUBING-MACHINE.

1,182,711.

Specification of Letters Patent.

Patented May 9, 1916.

Application filed June 12, 1914. Serial No. 844,835.

To all whom it may concern:

Be it known that I, VERNON ROYLE, a citizen of the United States, and resident of Paterson, in the county of Passaic and State of New Jersey, have invented a new and useful Improvement in Tubing-Machines, of which the following is a specification.

My invention relates to a tubing machine and more particularly to the head of the machine, with the object in view of providing a multiple strainer head which may also be employed as a multiple tube forming head, whereby the capacity of the tubing machine either for straining or tubing making, may be materially increased and all danger of overcrowding the machine with material avoided.

With these ends in view, my invention consists in certain features of construction and combinations of parts as will be herein-after more fully described and pointed out in the claims.

In the accompanying drawings, Figure 1 is a top plan view of the head portion of the machine. Fig. 2 is a view of the same in vertical section in the plane of the line A—A of Fig. 1. Fig. 3 is a transverse section in the plane of the line B—B of Fig. 2.

Fig. 4 is a partial face view of the strainer plate. Fig. 5 is a partial face view of the screen which is placed over the inner face of the strainer plate, and Fig. 6 is a portion of a die, core bridge and core which may be substituted for the strainer plate and strainer when the machine is used as a tube making machine instead of a straining machine.

The cylinder of the machine is denoted by 1, the stock worm by 2, and the body of the strainer head by 3. The body portion of the head is made fast to the end of the cylinder 1, by means of suitable bolts 5 and the interior of the body portion 3, when the head is in place, forms a continuation of the interior of the bore of the cylinder 1 and the stock worm 2 extends continuously from the interior of the cylinder into the interior of the head. The body of the head 3 is provided with a plurality of outlets, in the present instance three, one of these being in axial alinement with the stock worm and the other two being located at right angles to this one and placed diametrically opposite each other. These several openings are closed by hollow nuts denoted respectively by 6, 7 and 8, which screw into the mouths

of the openings and hold in place either the strainer plate or the die and core bridge as the case may be. The strainer plates are similar in construction. One of them, 60 shown in section in Fig. 2, is denoted by 9, and this is provided with polygonal shaped openings, in the present instance, openings substantially rectangular in shape, as denoted at 10, Fig. 4. These polygonal 65 shaped openings, as distinguished from the ordinary circular shaped opening, are of importance in the structure since they afford an opportunity of less area of web between the openings than where the round are employed, and give greater freedom for the escape of the material forced through the screen 11, placed over the inner face of the strainer plate.

The opposite sides of the head intermediate of the discharge openings, are covered by plates 12, 13, spaced from the body 3 of the head, to form chambers 14, 15, for the circulating of either a heating or a cooling liquid as may be desired, these chambers being in communication with each other by suitable ports 16, 17, see Fig. 3, which connect with annular passageways 18, 19, surrounding the lateral discharge openings, and by a port 20, with an annular 80 passage 21, surrounding the forward discharge opening. These chambers 14, 15, for the circulating medium, also communicate through ports 22, 23, with passages 24, 25, for the circulating medium, in a wall of the 85 cylinder 1.

The stock worm 2, has a gradually decreasing pitch from its rear toward its forward end, so that its power upon the material being operated upon is increased as 95 the material reaches the interior of the head.

The die, core bridge and core, in the present instance, a multiple core, are represented respectively by 26, 27, 28, in Fig. 6, and are of such dimensions that they will fit 100 the position occupied by the strainer plates 9 in the several discharge passages when it is desired to use the machine as a tube-making machine instead of a straining machine.

By constructing the head with a plurality 105 of discharge openings the stock worm may be used to its full capacity, the output being materially increased because there is no danger of overloading since the material will find relief through the lateral passages 110 when the forward discharge passage is overloaded, and furthermore, the several dis-

charge passages render it feasible to use a stock worm which will feed a much greater quantity for a cylinder of a given diameter than where one discharge opening alone is employed. The location of certain of the discharge openings at an angle to the forward discharge opening is also a feature of importance as it is found in practice that the forward opening will first be used to its full capacity and that only when it is overburdened, will relief take place in a lateral direction. I do not intend to limit myself, however, to the use of two lateral discharge openings in addition to the forward discharge opening, as the number may be one or more than two as may be found desirable.

What I claim is:

1. A tubing machine having a head provided with laterally disposed discharge

openings, chambers intermediate of said discharge openings for a circulating medium, and passages in said head for a circulating medium leading from said chambers and extending around said discharge openings. 25

2. A tubing machine having a head provided with a discharge opening, a strainer plate provided with polygonal shaped openings arranged to seat in the discharge opening and a screen in proximity to a face of 30 the strainer plate.

In testimony, that I claim the foregoing as my invention, I have signed my name in presence of two witnesses this fourth day of June, 1914.

VERNON. ROYLE.
